UNITED STATES PATENT OFFICE

2,363,109

VAPOR LAMP JACKET

Lawrence R. Keiffer, Cleveland Heights, Ohio, assignor to General Electric Company, a corporation of New York

Application April 1, 1942, Serial No. 437,288

3 Claims. (Cl. 176—122)

My invention relates to vapor discharge lamps, and its principal object is to provide a simple, effective, inexpensive, readily attachable and detachable light-transmitting, heat-retaining enclosure or jacket for such lamps. Another object of my invention is to provide a vapor discharge lamp enclosure which is constructed and arranged to be supported by the lamp and to constitute part of the lamp when so supported. A further object of my invention is to provide a simple mounting means for a light-transmitting, heat-retaining sleeve on a temperature sensitive, elongated lamp having bases secured to the ends thereof. Further objects and advantages of the invention will appear from the following detailed description of species thereof and from the drawing, in which:

Fig. 1 is a side, elevational, partly sectional view of a vapor discharge lamp unit embodying my invention;

Fig. 2 is a fragmentary, sectional, side-elevational view of one end of a lamp unit embodying my invention; and

Fig. 3 is a sectional view of a species of support member useful in the lamp unit illustrated in Fig. 2.

Referring to Fig. 1 of the drawing, the lamp unit illustrated comprises an elongated, tubular fluorescent lamp 10 and a tubular glass sleeve 11 surrounding the lamp 10. The sleeve 11 is supported by annular support members 12 and 13 disposed on the bases 14 and 15, respectively, of the lamp 10. The bases 14 and 15, which are somewhat smaller in diameter than the lamp envelope, are provided with a pair of contact pins 16 which support the unit and transmit electrical energy to the lamp electrodes 17 and 18 when inserted in suitable sockets, such as those disclosed in the U. S. Reissue Patent 21,545, issued August 27, 1940.

The lamp 10 is similar to those disclosed in the U. S. Patents 2,182,732, issued December 5, 1939, and 2,259,040, issued October 14, 1941, and comprises an elongated, tubular, sealed glass envelope containing a starting gas, such as argon, at a few millimeters pressure and a small quantity of mercury 19. The widely spaced electrodes 17 and 18 of the lamp 10 carry material of low work function, such as barium oxide. The inner surface of the envelope is coated with fluorescent material, indicated by the broken line in the drawing, which emits visible light under the influence of radiation from the electrically excited mercury vapor during operation of the lamp.

Lamps of this type are commercially available

10 in various lengths and diameters and are designed to have maximum light output when the temperature of the lamp envelope is about 100 to 120° F. and the air temperature is about 70 to 80° F. Changes in the environment of the lamp which lower the temperature of the lamp envelope cause the light output to decrease. For example, when the air temperature about the lamp envelope is approximately 30 to 50° F., the light output is then approximately only 60 to 80 per cent of the light output of the lamp at air temperatures of about 70 to 80° F. Drafts and lower air temperatures cause further diminution in the light output of the lamp.

20 The sleeve 11, the members 12 and 13, together with the bases 14 and 15 of the lamp 10, constitute an enclosure or jacket for the lamp envelope which effectively reduces the dissipation of heat from said envelope. A separation of the order of about one-quarter inch between the sleeve 11 and the envelope is preferred, though this may be varied somewhat for different conditions. When a separation of this order exists, the maximum light output of an enclosed lamp occurs at an air temperature of about 25 to 35° F.

25 The annular members or washers 12 and 13 preferably consist of compressible, flexible material, such as soft rubber, or other material capable of supporting the sleeve 11 on the bases 14 and 15 and of effectively sealing the space between the envelope and the sleeve 11. The outer diameter of the members 12 and 13 is slightly larger than the inner diameter of the sleeve 11 and the inner diameter thereof is slightly smaller than the diameter of the bases 14 and 15. The thickness of the members 12 and 13 is approximately the same as the width of the bases 14 and 15. The lamp unit is readily assembled by forcing one of said members 12 and 13 onto one of the bases 14 and 15, inserting the opposite end of the lamp into the sleeve, forcing the member 12 or 13 mounted on the base into the end of the sleeve 11, so that all these elements are flush as shown in the drawing, and then forcing the other annular member into the space between the opposite base and the open end of the sleeve 11. The members 12 and 13 are compressed between the sleeve 11 and the bases 14 and 15. The sleeve 11 is thus firmly supported in a fixed, spaced position with respect to the lamp 10. The sleeve 11 is readily removed from the lamp 10 by pushing against one of the bases of the lamp 10 with sufficient energy to force one of the members 12 and 13 out of the sleeve 10. This member is

then removed from the base and the lamp pulled out of the sleeve.

The embodiment of my invention illustrated in Fig. 2 of the drawing is similar in all respects to that illustrated in Fig. 1 except for the shape of the annular support member 20 and the length of the sleeve 11. In this embodiment, the annular member 20 has a ring-shaped or annular slot therein which is indicated at 21 in the drawing. The depth of the slot is slightly more than half the thickness of the member 20 and accommodates the end of the sleeve 11. The end portion of the sleeve 11 is embedded in or covered by the member 19 and is thus effectively protected from accidental contact with solid objects. The sleeve 11 is slightly shorter than the corresponding sleeve shown in Fig. 1 so that the outer surfaces of the base and the support member are flush. It will be understood that the opposite end of the lamp is the same structurally as the end illustrated.

The support member 22 illustrated in Fig. 3 of the drawing is similar to that illustrated in Fig. 2 except that the surfaces 22 of the slot are serrated to give a better gripping action on the end portion of the sleeve 11. As pointed out above, this support member is useful in the embodiment of the invention illustrated in Fig. 2 of the drawing.

Fluorescent lamps now commercially available have an outer diameter of about one inch, about 1½ inches, and about 2½ inches. It is particularly advantageous to use a sleeve having a diameter of 1½ inches for the one-inch lamp, and a sleeve having a 2½ inch diameter for the 1½ inch lamp since salvage tubing of the 1½ and 2½ inch size may be used as sleeves by the manufacturer.

While I have described my invention in conjunction with a fluorescent discharge lamp, it will be understood that I contemplate its use with other lamps similarly sensitive to changes in envelope temperature; for example, lamps similar to that illustrated in Fig. 1, except that the coating of fluorescent material is omitted and the lamp envelope is pervious to the radiation having a wavelength of 2537 Angstrom units emitted by the mercury vapor discharge, are commercially available. My heat-retaining enclosure is also useful in conjunction with such lamps when the sleeve 11 is of material pervious to the desired radiation.

The sleeve 11 may be partially coated with reflecting material, such as silver or aluminum, for purposes of shielding and light control. Fluorescent material may be disposed in or on the sleeve 11 when used with lamps emitting radiation capable of exciting such material.

What I claim as new and desire to secure by Letters Patent of the United States is:

10. A lamp unit comprising in combination an elongated gaseous electric discharge lamp having a base attached to each end thereof, and a heat conservator comprising an elongated glass sleeve surrounding said lamp and coextensive therewith and supported at each end by a washer of resilient material compressed between each base and the adjacent end of the sleeve, said washers effectively sealing the space between said lamp and sleeve, and said sleeve being imperforate so as to provide a dead air space around the lamp.

20. A lamp unit comprising in combination an elongated gaseous electric discharge lamp having a base attached to each end thereof, and a heat conservator comprising an elongated glass sleeve surrounding said lamp and coextensive therewith and supported at each end by a washer of resilient material tightly secured to and around each base, each of said washers being of larger outer diameter than said sleeve and having an annular slot in one of its faces between its inner and outer peripheries, the ends of said sleeve being secured in said slots and enclosed within said washers, said washers effectively sealing the space between said lamp and sleeve.

30. A lamp unit comprising in combination an elongated gaseous electric discharge lamp having a base attached to each end thereof, and a heat conservator comprising an elongated glass sleeve surrounding said lamp and coextensive therewith and supported at each end by a washer of resilient material tightly secured to and around each base, each of said washers being of larger outer diameter than said sleeve and having an annular slot with serrated surfaces in one of its faces between its inner and outer peripheries, the ends of said sleeve being secured in said slots and enclosed within said washers, said washers effectively sealing the space between said lamp and sleeve.
